FOREIGN PATENT DOCUMENTS

EM 000185798-0001 * 8/2004

Primary Examiner — Lakiya Rogers*Assistant Examiner* — Altaira Swangin(74) *Attorney, Agent, or Firm* — Alston & Bird LLP(57) **CLAIM**

The ornamental design for a handheld flashlight, as shown and described.

DESCRIPTION

FIG. 1 is a front perspective view of the design; FIG. 2 is a rear perspective view of the design; FIG. 3 is a side view of the design; FIG. 4 is a side view of the design; FIG. 5 is a top view of the design; FIG. 6 is a rear view of the design; FIG. 7 is a top view of the design; and, FIG. 8 is a bottom view of the design. Any broken line(s) shown are for illustrative purposes only and form no part of the claimed design.
